(57) **CLAIM**

The ornamental design for an inside pot for cooking appliance as shown and described.

DESCRIPTION

1. Inside pot for cooking appliance

1.1 : Perspective

1.2 : Front

1.3 : Left

1.4 : Top

1.5 : Bottom

1.6 : Perspective view 2

1.7 : Perspective view 3

1.8 : Perspective view 4

1.9 : Perspective view 5

Reproduction 1.2 is a front view of the inside pot for cooking appliance where the back view is a mirror image; reproduction 1.3 is a left view thereof where the right view is a mirror image; reproduction 1.6 is a perspective view showing the state of use that the accessory for stir-frying has been attached; reproduction 1.7 is a perspective view showing the state of use that the accessory for roasting has been attached; reproduction 1.8 is a perspective view showing the state of use that the accessory for boiling has been attached; reproduction 1.9 is a perspective view showing the state of use

(Continued)

that the accessory for deep-frying has been attached; this design is an inside pot for cooking appliance that can be easily removed from the cooking appliance by holding a handle without using an additional tool; since the upper handle part has a fixed rotating bearing structure, it is fixed even when the lower body part is rotated; as shown in reproductions 1.6 to 1.9, this design can be used with various detachable accessories for stir-frying, roasting, deep-frying, boiling, etc. The broken lines in reproduction 1.5 depict portions of the inside pot for cooking appliance that form no part of the claimed design. The broken lines in reproductions 1.6-1.9 show environmental structures that form no part of the claimed design.
